UNITED STATES PATENT OFFICE

2,494,071

DIE-CASTING APPARATUS

Charles C. Veale, Wheaton, Ill., assignor to Western Electric Company, Incorporated, New York, N. Y., a corporation of New York

Application November 11, 1943, Serial No. 509,866

1 Claim. (Cl. 22—68)

1

This invention relates to die casting apparatus and more particularly to mechanisms for controlling the operation of die casting machines.

It is an object of the present invention to provide a simple, reliable and automatic apparatus for controlling the sequence of operations of a die casting machine.

In accordance with one embodiment of the invention, cooperating hydraulic and electric circuits are so arranged that by the manipulation of a single valve which controls the supply of fluid under pressure to the ram of a die operating mechanism, a complete cycle of operation of the die casting apparatus is effected. In this cycle, the dies of the apparatus close, an injection plunger is advanced a predetermined distance at a relatively slow speed, is held stationary for a short interval, is then advanced relatively rapidly to make a die casting shot and is, after a predetermined interval, reset to its original position.

A complete understanding of the invention may be had by reference to the following detailed description when considered in conjunction with the accompanying drawings, wherein

Fig. 1 is a front elevational view of a die casting machine embodying the structural features of the present invention, and

Fig. 2 is a diagrammatic view of the electrical and hydraulic circuits constituting the preferred embodiment of the present invention.

In the drawings, particular reference being first had to Fig. 1, there is shown a die casting machine including framework, designated generally by the numeral 10, in which a cross head 11 may be reciprocated by a piston 12, which is adapted to be actuated by fluid under pressure admitted to a cylinder 13 through either a port 14 or a port 15. The cross head 11 has suitably fixed to it an upper movable die member 16 for cooperation with a stationary die member 17 seated upon a bolster 18, which is, in turn, suitably mounted in the framework 10. Extending partly under the bolster 18 is a melting pot 19, in which there is formed a gooseneck 20 for directing die casting material upwardly through a nozzle 21 to the die members 16 and 17. The gooseneck 20 is in communication with a shot cylinder 22, into which die casting material may pass through suitable apertures 23 for transference to the dies. The shot cylinder 22 has a shot plunger 24 positioned therein, which may be reciprocated by a head member 25, to which the shot plunger may be suitably connected by means of a connecting member 26. The mecha-

2

nism described thus far is shown in detail in the co-pending application of George L. Cherry and Charles C. Veale, Serial No. 498,079, filed August 10, 1943, now matured into Patent No. 2,393,588 wherein various features of the mechanism are described specifically and claimed. The head member 25 is adapted to be reciprocated by a piston rod 30 (Fig. 2) and will, at predetermined times, to be described more in detail hereinafter, actuate a switch 27, which may be enclosed in a suitable housing 28 (Fig. 1) attached to the framework 10, being suitably mounted on a housing 29 (Fig. 1) which encloses the various actuating and controlling means shown in Fig. 2.

Mounted within the housing 29 (Fig. 1) are a pair of aligned cylinders 35 and 36, in which pistons 37 and 38, respectively, are reciprocated. The piston 38 has a piston rod 39 attached to it for normally limiting the upward movement of the piston 37 when the piston 38 is in the position shown in Fig. 2. The piston 38 is normally held in the position shown in Fig. 2 by fluid under pressure from a suitable source (not shown) directed through a valve 40 and entrance port 41 to the upper end of the cylinder 36. If it is desired to move the melting pot 19 for any reason, the plunger 24 may be withdrawn from the cylinder 22 by reversing the valve 40 and permitting fluid under pressure acting against the underside of the piston 37 to move the piston 38 upwardly, thus to withdraw the plunger 24 completely from the shot cylinder 22. In the normal operation of the apparatus, the piston 38 and piston rod 39 are always maintained in the position shown, where they will limit the upward movement of the shot plunger 24 to approximately that shown in Fig. 1, where its lower end is just above the inlet apertures 23 from the melting pot to the shot cylinder 22. It should be noted at this time that if fluid under the same pressure is fed into the opposite ends of the cylinder 35, the piston 37 will be moved downwardly due to the differential pressure exerted thereon because of the difference in effective area of the top and bottom faces of the piston 37.

The cylinder 35 may be supplied with fluid under pressure through either an upper entrance port 42 or lower entrance port 43 upon the proper manipulation of a pair of slide valve members 44 and 45 slidably positioned in a valve block 46. The slide valve member 44 is provided with a pair of relatively small passageways 60 and 61 formed in it and a pair of relatively large passageways 62 and 63, through which fluid under pressure may be selectively directed to the

ports 42 and 43, depending upon the position of the slide valve member 44 within the valve block 46. The slide valve member 45 is provided with a pair of relatively large passageways 64 and 65 and a relatively small passageway 66, through which fluid under pressure may be directed through passageways in the block 46 and through the passageways in the slide valve member 44.

Fluid under pressure from a suitable source (not shown) is supplied to a large entrance port 67 and a small entrance port 68 in the valve block 46 and the fluid driven out of the cylinder 35 may return to the source through an exit port 69 formed in the valve block 46.

The position of the slide valves 44 and 45 in the valve block 46 may be controlled by a pair of solenoid-actuated slide valves, designated generally by the numerals 75 and 76. The solenoid-actuated slide valves 75 and 76 have entrance ports 77 and 78, respectively, connected to the source of fluid under pressure and have exhaust ports 79 and 80 and 81 and 82, respectively, which are connected to return pipes 83 and 84, respectively, for conducting spent fluid back to the source of fluid under pressure. The valve 75 has a slide valve 85, which may be shifted to either one of two positions upon the selective energization of a solenoid 86 or a solenoid 87 and, similarly, the valve 76 has a slide valve member 88 which may be selectively shifted to either one of two positions upon the selective energization of the solenoids 89 and 90. When the slide valve member 85 is in the position shown in Fig. 2, fluid under pressure will be directed through the entrance port 77 to the slide valve member 85 and through a pipe 91 against the upper end of the slide valve member 44 in the valve block 46 and fluid in the lower end of the valve block 46 will pass out through pipe 92 past the slide valve member 85 through exhaust port 80 and thus back to the source of fluid under pressure. When the position of the slide valve member 85 is reversed from that shown in Fig. 2, the slide valve member 44 will be shifted to its upper position opposite to that shown in Fig. 2 due to the shifting of the slide valve member 85 to interconnect the entrance port 77 thereof with pipe 92 and to interconnect pipe 91 with the exhaust port 79.

In the position shown, the slide valve member 88 interconnects the entrance port 78 with pipe 93 and thus fluid under pressure will be forced against the upper end of the slide valve member 45 in valve block 46. When the slide valve member 88 is in the position shown, fluid entrapped beneath the lower end of the slide valve member 45 may be forced through a pipe 94 and through valve 76 to an exhaust port 82 and thus back to the source of fluid under pressure.

Power for energizing the solenoids 86, 87, 89 and 90 is supplied from a suitable current source 101 through a main control switch 102, which may be closed to prepare the apparatus for operation. The slide valves 75 and 76 are of the type which may be shifted from one position to the other and when so shifted, will remain in their shifted position until the opposite one of the solenoids associated therewith is energized. Solenoid 86 is adapted to be energized upon the closure of a plunger-operated switch 103, solenoid 87 is adapted to be energized upon closure of a switch 104, solenoid 89 is adapted to be energized upon the closure of a switch 105 forming part of a time delay relay 106, and solenoid 90 is adapted to be energized upon the closure

of the switch 27. The time of operation of the various switches which close the solenoids will be described more in detail with the description of the operation of the apparatus.

Fluid under pressure may be supplied from a suitable source, not shown, through a port 107 and through a manually operable main valve 108 to move the piston 12 upwardly or downwardly to open or close the dies of the apparatus by raising or lowering the upper die member 16. In the diagrammatic illustration in Fig. 2, the piston 12 has an enlarged head portion 109, which is shown in its upper position, to which it has been raised by shifting the valve 108 to permit the passage of fluid under pressure therewith and through the port 14 to the underside of the piston head 109, a suitable packing gland 110 being provided to close that portion of the lower end of the cylinder 13 which is not filled by the piston 12. The port 14 is connected to the valve 108 by means of a pipe 111 in communication with which there is a relatively small pipe 112 which leads to the upper end of a control cylinder 113. The control cylinder 113 has a piston 114 in it, which serves to actuate a piston rod 115 carrying at its lower end a valve member 116 which is normally urged to engage a valve seat 117 in the cylinder 13 by a compression spring 118 interposed between an upper surface of the cylinder 13 and a disc 119 attached to the piston rod 115. The interior of the cylinder 13 has a bore 125 which conforms to the size of the piston head 109 and it is gradually reduced to a relative small bore 126, into which a reduced portion 127 of the piston 12 may move a short distance. A bleeder passage 128 interconnects the small bore 126 with the upper portion of the large bore 125, so that these two chambers are in communication. The purpose of this construction will become apparent as the description progresses. The lower end of the cylinder 113 has a pipe 129 communicating therewith, which is in communication with a pipe 130 interconnecting the port 15 and a port 131 in the valve 108, whereby when the valve 108 is moved to the position opposite to that shown in Fig. 2, fluid under pressure supplied through port 107 will pass out through port 131 into pipes 130 and 129 and reverse the position of the piston 114 in the cylinder 113. The pipe 130 also has a pipe 132 in communication therewith which extends to a control cylinder 133 having a piston 134 in it which is normally urged to its downward position, as shown in Fig. 2, by a compression spring 135, but which may be moved upwardly against the action of the spring 135 to, through the action of a plunger 136, close the plunger-actuating switch 103. Seated in the port 15 is a valve member 137, which is normally urged to seat against a valve seat 138 by a compression spring 139 engaging an upper surface of the cylinder 13 and bearing against a disc 140 attached to a valve stem 141 which carries the valve member 137. The cylinder 13 is provided with an upper chamber 142, in which the compression springs 118 and 139 are positioned and this chamber may be sealed from communication with the small bore 126 of the cylinder 13 by the valve head 116. However, when the valve head 116 is disengaged from the valve seat 138, any fluid which may be in the upper portion of the cylinder 13 will be permitted to pass out through the chamber 142 to a pipe 143 which returns the fluid to the fluid pressure source.

75 The cross head 11 carries a switch-actuating

member 144, which is adapted to close the switch 104 when the cross head 11 moves downwardly and, similarly, the head member 25 on the piston rod 38 carries a switch-actuating member 145, which is adapted to close the switch 27. In this manner, these two switches may be closed to supply current from the source 101 through the main switch 102 to their respective solenoids. The switch 103, when closed by the plunger 136, will supply power to the solenoid 86 and also to the time delay relay 106, thus to initiate the operation of the time delay relay 106 at the same time that the solenoid 86 is energized. The time delay relay 106 is set to close its switch 105 a predetermined length of time after the switch 103 closes and when switch 105 closes, it will energize its associated solenoid 89.

A more complete understanding of the apparatus may be had by reference to the following brief description of the mode of operation thereof. The closure of the switch 102 and the initiation of the operation of the mechanism for supplying fluid under pressure to the various parts of the apparatus will place the apparatus in condition for operation. After the melting pot 19 is in the proper position, and the piston 38 has been set in the position shown in Fig. 2, and a supply of molten metal is in the melting pot 19, the apparatus may be operated to die cast parts conforming to the shape of the die members 16 and 17. The operation of the apparatus is initiated by reversing the valve 108 from the position shown in Fig. 2. When the valve 108 is moved to the position opposite to that shown in Fig. 2, fluid under pressure through port 107 will be directed to the pipe 130 and fluid in the lower end of the cylinder 12 will be permitted to escape through the valve 108 in its reverse position. Fluid under pressure being admitted through the pipe 130, will pass first through port 15 and will force the valve head 137 downwardly against the action of its associated spring 139, to pass into the upper end of the cylinder 13. Simultaneously with the supplying of fluid under pressure through the entrance port 15, fluid under pressure will be supplied through pipe 129 to raise the piston 114 and the fluid in the upper end of cylinder 113 will pass through pipes 112 and 111 and valve 108 back to the source of fluid under pressure. In this manner, the valve head 116 will be seated in the valve seat 117 and the fluid admitted to the upper end of the cylinder 13 will not be permitted to pass out through chamber 142 and pipe 143, but will actuate the piston head 109 and start its downward movement. The piston 134 in the cylinder 133, will not, at this time, be operated since the compression spring 135 is sufficiently strong to prevent the piston 134 from moving upwardly until the upper die member 16 engages the stationary die member 17 and pressure is thus built up within the cylinder 125. As the piston head 109, piston 12 and the cross head 11 move downwardly, the switch-actuating member 144 will, in its movement downwardly with the head 11, momentarily close switch 104 to supply power for energizing the solenoid 81. Energization of solenoid 81 will shift the slide valve member 85 from the position shown to its lowermost position and fluid under pressure supplied through entrance port 71 will be directed through pipe 92 to the underside of the slide valve member 44, thereby to shift it to its upper position. When the slide valve member 44 is shifted to its upper position, passageway 61

therein will interconnect the small entrance port 68 with the lower entrance port 43 of cylinder 35 and passageway 62 will connect a large entrance port 67 through passageway 66 to entrance port 42 of the cylinder 35. In this manner, fluid under pressure will be supplied to both the upper and lower surfaces of the piston 37. Since the upper effective surface area of the piston 37 is larger than the lower surface thereof, piston 37 will be moved downwardly slightly by the difference in effective pressure of the fluid supplied to the opposite sides thereof and will carry the head member 25 downwardly to move the shot plunger 24 below the apertures 23 and thus entrap a shot of molten metal in the gooseneck 20. As the head member 25 moves downwardly, the switch-actuating member 145 will momentarily engage and close a switch 27, thus to supply power to the solenoid 90 and thereby shift the slide valve member 88 from the position shown to a position opposite to that shown where fluid under pressure through the entrance port 78 will be directed to the lower surface of the slide valve member 45 to raise the slide valve member 45. It will be understood that when the slide valve member 45 moves upwardly, the fluid in the upper end of the valve block 46 will be forced through the pipe 33 and exhaust port 81 and back to the fluid source and that, similarly, when the slide valve member 44 moves upwardly, fluid between the upper end thereof and the top wall of the block 46 will be directed through the pipe 91 and valve 75 through exhaust port 79. When the slide valve member 45 is moved upwardly, all of the passages in the block 46 communicating with the entrance ports 67 and 68 and exhaust ports 69 will be blocked by either slide valve member 44 or slide valve member 45 and this condition will prevail until the upper die member 16 tightly engages the stationary die member 17 and pressure builds up in the pipe 130 to such an extent that the piston 134 will be raised. As soon as the piston 134 is raised, it will close switch 103 through its plunger 136 and will energize solenoid 86, thus to reverse the position of the slide valve member 85 and return it to the position shown in Fig. 2. When slide valve member 85 is moved back to the position shown in Fig. 2, entrance port 67 will be interconnected with upper entrance port 42 of the cylinder 35 through the large passageways 64 and 62 in the slide valve members 45 and 44, respectively. Similarly, port 43 of cylinder 35 will be connected to exhaust port 69 through large passageways 63 and 65 in slide valve members 44 and 45. Thus, a relatively large amount of fluid under pressure will be directed against the upper surface of the piston 37 to force the piston 37 rapidly downwardly to inject a portion of the molten metal trapped in the gooseneck up into the die members 16 and 17. The construction of the cylinder 13 and valve members 116 and 137 is such that, when pressure in the upper end of the cylinder and in pipe 130 is at its highest point, valve member 137 will seat against valve seat 138 and valve member 116 will seat against valve seat 117, thus sealing the upper end of the cylinder. When the shot plunger 24 injects the molten metal into the die cavity, piston head 109 will tend to move upwardly, but the head of fluid in the upper end of the cylinder 13 will only force the valve members 116 and 137 more firmly into engagement with their associated valve seats and will prevent the upward movement of the die member 16.

As the switch 103 was closed to initiate the op-

7

eration of the shot plunger in injecting a shot into the die member, the circuit to time delay relay 106 was also completed, thus initiating operation of this relay, and after a predetermined selected interval, relay 106 will close its switch 105, thus to supply current to solenoid 89 to effect the return of slide valve member 88 to its normal position, as shown in Fig. 2. When the slide valve member 88 returns to the position shown in Fig. 2, slide valve member 85 having been returned to its upper position, the apparatus will be restored to the condition shown in Fig. 2, where the upper entrance port 42 of cylinder 43 will be in communication with the exhaust port 69 in the block 46 and where entrance port 68 will be in communication through passageways 65 and 80 with the port 43, thus to return the shot plunger to its normal position by raising the piston 37. In this manner, the portions of the apparatus which inject the shot of molten metal between the die members 16 and 17 will be restored to normal condition and the return of the valve 108 to the position shown in Fig. 2 will restore the die 16 to its upper position in the following manner: When the valve 108 is moved from the position opposite to that shown in Fig. 2, back to the position shown in Fig. 2, fluid under pressure will be directed through port 107 to pipes 111 and 112. The fluid under pressure directed through the port 14 from pipe 111 will be ineffective to raise the piston head 109 due to the fact that the upper end of the cylinder 13 has been closed off from communication with the chamber 142 by the valve member 116 and the valve member 137 has blocked the flow of fluid out of the cylinder 13 through port 15. Therefore, the first operation that takes place is the return of the piston 114 to the position shown due to the supply of pressure to the upper end thereof and the return of fluid to the lower end thereof through pipe 29 and pipe 130. When piston 114 moves downwardly, the upper end of the cylinder 13 will be in communication with the chamber 142 and fluid may thus pass from the upper end of the cylinder 13 out through the pipe 143 and back to the fluid source. In this manner, the piston 12 will be moved upwardly quite rapidly until it approaches the upper end of its travel, at which time the reduced portion 127 of the piston head 129 will enter the small bore 126 and the escape of fluid from the upper end of the cylinder 13 will all be through the bleeder passage 128, thus to cushion the upper movement of the piston 12. As soon as the valve 108 is moved back to the position shown in Fig. 2, the pressure against the piston 134 will, of course, be released and the switch 103 will be opened, thus to restore the entire apparatus to the position shown in Fig. 2.

8

It should be noted that the switch-actuating members 144 and 145 on the heads 11 and 25 are ineffective to operate their respective switches on the upward movement of the heads.

5 What is claimed is:

An apparatus for injecting casting material into a mold having a cylinder and piston for closing the mold and a hydraulic cylinder and piston for injecting material into the mold, comprising hydraulic means for moving the molding piston to close the mold, means for locking the mold-closing piston at the end of the closing movement, a first two-position valve in the hydraulic lines to the injection cylinder and movable to its second position in response to the movement of said closing piston to actuate the injection piston to a ready position, a second two-position valve in the hydraulic lines leading to said first two-position valve and movable to its second position in response to the movement of the injection piston to its ready position to lock the injection piston in place, an auxiliary piston connected to the mold closing cylinder so that it is responsive to the building up of a hydraulic pressure on the mold-closing piston after closing of the mold, said auxiliary piston being connected to the operating mechanism of said first two-position valve to cause retraction of said first two-position valve to its first position, said retraction of the first two-position valve being effective to unlock the injection piston and initiate a rapid actuation of the injection piston, a time delay device operated by said auxiliary piston for causing retraction of said second two-position valve to its first position, 10 said retraction of the second two-position valve being effective for restoring the injection piston to normal position, and a manually operated valve for unlocking and restoring the molding piston to normal position.
